CLAIM

The ornamental design for a telephone receptacle, as shown and described.

DESCRIPTION

FIG. 1 is a front, top, and left side perspective view showing our new design for a telephone receptacle;

FIG. 2 is a rear elevational view thereof;

FIG. 3 is a left elevational view thereof; and,

FIG. 4 is a bottom plan view thereof, the four groups of broken lines depicting apertures for receiving a strap being for illustrative purposes only and forming no part of the claimed design.
